(57) **CLAIM**

The ornamental design for a sleeve case for electronic device, as shown and described.

DESCRIPTION

FIG. 1 shows a front view of a design of a sleeve case for electronic device, where an opening for the case is in a closed position.

FIG. 2 shows a back view of FIG. 1, where an opening for the case is in a closed position.

FIG. 3 shows an upper-side view of FIG. 1, where an opening for the case is in a closed position.

FIG. 4 shows a lower-side view of FIG. 1, where an opening for the case is in a closed position.

FIG. 5 shows a left-side view of FIG. 1, where an opening for the case is in a closed position. A right-side view of FIG. 1 is a mirror image of FIG. 5.

FIG. 6 shows an upper-side view of FIG. 1, where an opening for the case is in an open position.

FIG. 7 shows a left-side view of FIG. 1, where the opening for the case is in an open position.

FIG. 8 shows a front perspective view of FIG. 1, where the opening for the case is in an open position; and,

FIG. 9 shows a front perspective view of FIG. 1, where the opening for the case is in a closed position.

The broken lines represent environment and form no part of the claim. The boundary lines represent the boundary of the claim and form no part thereof.
